UNITED STATES PATENT OFFICE.

LOUIS L. DRIGGS, OF NEW YORK, N. Y.

DESIGN FOR AN AUTOMOBILE BODY.

60,516.

Specification for Design.

Patented Mar. 7, 1922.

Application filed February 23, 1921. Serial No. 447,326. Term of patent 7 years.

To all whom it may concern:

Be it known that I, LOUIS L. DRIGGS, a citizen of the United States, residing at New York city, in the county of New York and State of New York, have invented a new, original, and ornamental Design for Automobile Bodies, of which the following is a specification, reference being had to the accompanying drawings, forming a part thereof, in which—

Figure 1 is a plan view of the ornamental automobile body with the cover removed.

Figure 2 shows a side elevation of the automobile body with the cover in place; and

Figure 3 is a front elevation of the construction shown in Figure 1.

I claim:

The ornamental design for an automobile body as shown.

LOUIS L. DRIGGS.
